UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

PROCESS FOR MAKING RIBBED EXPANDED-METAL STRUCTURES.

1,145,342.

Specification of Letters Patent.

Patented July 6, 1915.

Application filed June 14, 1913. Serial No. 773,650.

To all whom it may concern:

Be it known that I, HERBERT E. WHITE, a citizen of the United States, residing at Youngstown, in the county of Mahoning and State of Ohio, have invented certain new and useful Improvements in Processes for Making Ribbed Expanded-Metal Structures, of which the following is a specification.

- 10 The present invention relates to a novel and practical process for making ribbed expanded sheet metal products, and the object is to provide a process that may be successfully and commercially employed to slit 15 and expand inside areas of a metal sheet, as distinguished from processes wherein the slitting and expanding is worked from an external edge of the blank inwardly, and also to develop and produce relatively deep 20 grooves between the slitted and expanded portions, making the formation of said grooves an instrumentality in the operation of straightening the slitted and expanded portions into final position.
- 25 A general object of the invention is to obviate the difficulties experienced in expanding the slitted portions between the ribs of ribbed sheet metal products by first expanding the slitted portion, and making 30 provision for the increased area of the expanded section by causing the slitted portion to move to one side of the plane of the original sheet, while it is undergoing the act of being expanded, so that the expansion 35 of the slitted material is effected without any movement of the uncut area from which the ribs are to be formed. And, thereafter, subjecting the sheet to an operation that channels the unslotted areas with relatively 40 deep grooves which produce stiffening ribs for the structure. The effect of this subsequent channeling or grooving step is to exert a lateral draw upon the previously expanded portions with the result of partly 45 spreading the latter by moving the same toward the plane of the original sheet. Then, as a final operation, the completed ribs are laterally spread or separated to a greater distance apart in order to complete 50 the spreading of the previously expanded portions by moving the latter into the flat plane of the sheet. In this connection, it will be observed that two operations are involved to bring the previously slit and 55 expanded portions into a flat plane, namely

that of grooving the unslotted areas to produce the ribs, and the final step of laterally widening the distance between the ribs, and both of which operations are performed without further expanding the slotted areas. 60 It will also be noted that these operations provide for the production of a ribbed expanded product which in its final form is of greater width than the original blank. Accordingly, provision is made by the present process whereby the lateral movement or spreading of the slitted and expanded portion of the sheet into a flat plane is more than enough to furnish stock for the ribs. 65

In carrying out the process, any suitable 70 instrumentalities or mechanisms may be employed which are available, or can be adapted, for the purpose, so for illustrative purposes there are only shown in the drawings, diagrammatically, such views as may 75 be necessary for a full understanding of the manipulation of the metal sheet to develop and produce, in a rapid and economical manner, the expanded metal structure.

In these drawings Figure 1 is a plan view 80 of the metal sheet as affected by the first step of the process, namely that of slitting and expanding inside areas between at least two unslotted areas. Fig. 2 is a cross sectional view on the line 2—2 of Fig. 1. Fig. 85 3 is a longitudinal sectional view on the line 3—3 of Fig. 1 to show, in side elevation, the expanded area as produced by the first step of the process. Figs. 4, 5 and 6 are diagrammatic views of the metal sheet illustrative of the successive operations which are performed to bring the slitted and expanded areas into substantially the plane 90 of the original sheet. Fig. 7 is a diagrammatic plan view of a type of combined 95 grooving and spreading machine that may be utilized for the final step of the process.

Like reference characters designate corresponding parts in the several figures of the drawings. 100

The first step in the process is to simultaneously slit and expand certain areas of a sheet metal blank. This may be accomplished by any suitable mechanism or apparatus available for the purpose, but preferably by means of combined cutting and displacing dies having the structural characteristics, arrangement, and operation of the dies disclosed in my former Patent No. 1,049,632, dated January 7, 1913. Accordingly, the first 110

stage in the manipulation of the metal sheet is to subject the same to an operation which produces in the sheet separate lines of interrupted longitudinal slits 1, which are arranged alternately in adjacent lines, and simultaneously displacing or offsetting to one side of the plane of the original sheet the individual strands or ribbons of metal formed between the slits. Also in this combined slitting and expanding operation, a desirable feature may be the elongating or stretching of the strands of metal between the slits, effected, for instance, by the means suggested in my aforesaid patent, but irrespective of the stretching of the strands, the slitting and expanding step acts to displace all of the meshed web to one side of the sheet, the same taking the form of a V-shaped trough-like arch *a*, as best seen in Fig. 2 of the drawings.

When the combined slitting, expanding and deforming step is completed, represented by the diagrammatic view of Fig. 4 of the drawings, the next step of the process is to subject the metal sheet to a channeling or grooving operation that channels the blank unslotted areas *b* with relatively deep grooves which produce stiffening ribs *r* between the expanded portions *a*. This rib-forming operation may be performed in any suitable manner and by any suitable instrumentalities, such for instance as by the means shown in my former Patent No. 1,056,871, dated March 25, 1913, but for illustrative purposes, there is suggested in Fig. 7 of the drawings a means that may be resorted to for not only the step of grooving the unslotted portions of the sheet to produce the ribs, but also for performing the operation of laterally separating the completed ribs to bring the expanded portions to the final position within substantially the plane of the sheet. This type of grooving and spreading machine that may be employed consists of any required number of graduated grooving units, each of which units includes successively arranged sets of upper and lower complementary die rolls 3—3 as indicated in Figs. 5 and 6, and suitable guides between the succeeding sets of rolls. This is plainly shown by Fig. 7 of the drawings, and it will be understood that the die rolls are arranged in parallel rows on parallel shafts, but necessarily are successively of a graduated construction to provide for progressively deepening and narrowing the grooves until the same reach the full depth to provide the finished ribs *r*. Beyond the point where the ribs have been completely formed in the said grooving and spreading machine, the die rolls are of the same construction and size as the preceding sets of rolls, but are divergently arranged, as indi-

cated in Fig. 7, in order to provide a means for drawing apart or separating the ribs to 65 the necessary extent for bringing the expanded portions into their final plane, that is, into substantially the plane of the sheet.

The foregoing operations are made plain by reference to the diagrams of Figs. 4, 5, 70 and 6 of the drawings, wherein Fig. 4 illustrates the metal shape as produced by the first step of the process, that is, having the slotted and expanded portions displaced to one side of the plane of the sheet. Fig. 5 75 illustrates that stage of the process wherein the ribs *r* have been completely formed by the action of the grooving machine, and said view illustrates the feature of the rib-formation constituting an instrumentality to 80 assist in the lateral spreading of the slotted and expanded portions, so that by the time the ribs have been completely formed, the said slotted and expanded portions have been partly spread laterally, that is moved 85 partly toward the flat plane. And, in Fig. 6 of the drawings is illustrated the final step of the process, wherein the finished ribs are laterally spread apart to the required extent to bring the slotted and expanded portions into the flat plane without expansion 90 thereof. Also the said series of diagrams 4, 5 and 6 illustrate the feature of the process producing a final product of greater width than the original blank.

From the foregoing, it is thought that the novel process steps will be readily apparent without further description, but it will be understood that any minor changes in the operations involved or in the means employed in connection therewith may be resorted to wherein the principle of the invention is retained.

I claim:

The method of making expanded metal 105 structures which consists in slitting, and stretching a longitudinal inside area of a metal sheet, leaving an uncut area on both margins of the slotted area, and simultaneously with the slitting operation, deforming 110 the entire section of material between the uncut areas into a trough form depressed to one side of the original plane of the sheet, thereby producing open meshes, then grooving the uncut areas to thereby produce finished ribs and to also thereby partly straighten the expanded troughed section, and subsequently moving the finished ribs laterally to thereby bring the partly straightened section into the flat plane.

In testimony whereof I hereunto affix my signature in the presence of two witnesses.

HERBERT E. WHITE.
